UNITED STATES PATENT OFFICE.

WILLIAM N. DAMON, OF SAN FRANCISCO, CALIFORNIA.

DISPENSING FAUCET.

Application filed January 29, 1923. Serial No. 615,623.

To all whom it may concern:

Be it known that I, WILLIAM N. DAMON, a citizen of the United States, and a resident of San Francisco, county of San Francisco, State of California, have invented a new and useful Dispensing Faucet, of which the following is a specification.

The present invention relates to improvements in dispensing faucets and has particular reference to a faucet intended to be used in connection with soda fountains such as are commonly used for the dispensing of root beer, coca cola, ginger ale and the like. The particular object of the invention is to provide a faucet that will allow different kinds of syrups to be dispensed in combination with carbonated water and that will cause the syrup to be mixed with the carbonated water within the faucet. A further object of the invention is to provide means in combination with the faucet causing the supply of carbonated water to be replenished each time a portion of the same is withdrawn for the purpose of serving a drink. A further object of the invention is to provide means in combination with the faucet for replenishing a supply of carbonated water independent of the withdrawal of the same. Further objects and advantages will appear as the specification proceeds.

The preferred form of my invention is illustrated in the accompanying drawing in which Figure 1 represents a vertical section through my device as adapted to a dispensing barrel, Figure 2 a top plan view of the same, Figure 3 a vertical section through a valve used in combination with my faucet for replenishing a supply of carbonated water while the faucet is rotated into an operative position, Figure 4 an enlarged detail view in vertical section of the interior parts of my faucet, Figure 5 a horizontal section through the same along line V—V of Figure 4, Figure 6 a vertical section taken along line VI—VI of Figure 5, Figure 7 a vertical section taken along line VII—VII of Figure 5 and Figure 8 a vertical section along line VIII—VIII of Figure 5. While I have shown only the preferred form of the invention it should be understood that various changes or modifications may be made within the scope of the claims hereto attached without departing from the spirit of the invention. It should be particularly understood that

while in the following description my device is described as dispensing three different syrups, namely those of root beer, coca cola and ginger ale it should not be construed as confined to those three particular syrups.

My faucet (1) is secured in the side of a dispensing barrel (2) well known in the art and therefore not illustrated in detail. It might be briefly explained that the barrel contains means for carbonating water, fresh water being supplied to the same through the pipe (3) from any suitable supply such as the city water pipes, and entering the pipe from below as viewed in Figure 1. The carbonated water communicates with the faucet through the tube (4). The dispensing barrel also contains three receptacles containing syrups of coca cola, root beer and ginger ale respectively, the coca cola entering the faucet through the pipe (6), the ginger ale through the pipe (7) and the root beer through the pipe (8) and all the pipes including the one carrying the carbonated water are arranged vertically above one another as shown in Figures 1 and 4. From the barrel extends outwardly an embossment (9) to which the housing (11) of my faucet is secured by means of a threaded sleeve (12), a suitable washer (13) being interposed between the housing of the faucet and the embossment. The housing itself is provided with four ports (14), (16), (17) and (18) communicating with the four pipes (4), (8), (7) and (6) respectively, the four ports being in a separate block (11') slidable in the housing and having a concave end terminating in the vertical bore (19) of the faucet with a gasket (21) having perforations registering with the ports interposed between the housing and the valve (22) in the bore of the housing. The latter valve 22 is a straight cylinder and is adapted to be rotated in the housing by means of a handle (23) and is provided for selective alignment with the port (14) through which the carbonated water is dispensed with five radial passages (24), (26), (27), (28), and (29), disposed in peripherally spaced relation, each passage communicating with a vertical discharge passage (31), (32), (33), (34) and (36). It will be seen that when the valve is in the position indicated in Figures 1, 2 and 5 none of the passages within the valve registers with the port (14) and this position will there-

fore be referred to as the neutral position. The passage (26) is smaller in diameter than the other passages and is designed to dispense carbonated water in a fine spray. 5 Its discharge passage (32) is disposed in the center of the valve while the other discharge passages are arranged at a radial distance from the said center.

The cylindrical valve is adjusted against 10 interleakage of the various ports by drawing it up as tightly as desired against the gasket (21) by means of the nut 12.

The valve normally occupies the position 15 shown in the drawings, that is the neutral position. If the valve as viewed in Figure 2 is revolved anti-clockwise into the first position shown in dotted lines the passage (26) is brought into registry with the port (14) and a fine spray of carbonated water is dispensed. If it is further revolved into the 20 second position the passage (24) registers with the port (14) and carbonated water is dispensed in a coarse spray. If the valve is turned clockwise as viewed in Figure 2 25 into any of the three positions shown in dotted lines a coarse spray of carbonated water will be delivered.

The valve is also provided with three 30 radial ports (37), (35) and (39) disposed in the vertical planes of the three passages (24), (28) and (29) and in the horizontal planes of the three ports (16), (17) and (18) respectively, and these three passages (37), (35) and (39) also communicate with 35 the vertical discharge passages (31), (34) and (36) respectively so that when they are brought into registry with the ports (16), (17) and (18) respectively they will allow one of the syrups to be delivered into a vertical discharge passage, while at the same 40 time carbonated water is delivered into the same passage and mixes with the syrup within the valve, dropping on the mixing cup (41) in its mixed form.

In recapitulation and with reference to 45 Figure 2 designating the various positions of the handle of my faucet and to the other figures for the cooperative arrangement of the various ports and passages, the complete 50 operation of the valve may be described as follows: Turning the valve from the neutral position shown in full lines in Figure 2 counter-clockwise into the first position indicated in dotted lines will cause the 55 passage (26) to register with the port (14) and will cause a fine spray of carbonated water to be dispensed. Turning it farther into the second dotted line position will cause the passage (24) to register with the 60 port (14) and also the passage (37) to register with the port (16) communicating with the root beer supply so that root beer and carbonated water will be simultaneously delivered into the discharge passage (31) and 65 will be mixed in said passage before drop-

ping on the mixing cup (41). Turning the handle clockwise into the first dotted line position shown in Figure 2 will cause the passage (27) to register with the port (14) 70 allowing carbonated water to be delivered into the discharge passage (33) in coarse form. Turning it farther into the second dotted line position causes the passage (28) to register with the port (14) for the delivery of carbonated water and also causes 75 the passage (35) to register with the port (17) communicating with a supply of ginger ale, thus allowing ginger ale and carbonated water to be simultaneously delivered into the discharge passage (34) and 80 to be mixed therein. Turning the handle farther into the last dotted line position causes the passage (29) to register with the port (14) while the passage (39) is brought in registry with the port (18) communicating with the coca cola supply whereby coca cola and carbonated water is delivered simultaneously into the discharge passage (36). 85

In combination with this dispensing 90 faucet I provide means for controlling the supply of water into the carbonator by means of the valve (42) introduced into the pipe (3). The latter is shown in detail in 95 Figure 3 and comprises a housing (43) communicating at opposite ends (44) and (46) with the pipe (3) and provided with a valve seat (47) disposed so as to accommodate a valve (48) having its axis arranged transversely to the direction of the pipe. The 100 valve is normally forced on its seat by means of a spring (51) bearing at its far end on a cap (52) threadedly secured on the housing. From the valve extends a valve stem (53) supported in the housing as shown at 105 (54) and engaging with its far end (56) a toothed disc (57) associated with the valve (22) and rotated with the same by means of the handle (23). While the handle is in 110 a neutral position or in any one of the dispensing positions previously mentioned the 110 end of the valve stem (53) engages a groove of the toothed disc and allows the spring (51) to close the valve (48) but while the valve (22) is turned from the neutral position to an operative position or vice versa 115 or between operative positions the valve stem (53) has to pass one of the teeth and causes the valve (48) to be lifted off its seat thus allowing the carbonator within the dispensing barrel to receive a fresh supply of 120 water before and after each operation. In case this automatic means for replenishing the supply of carbonated water is not sufficient the operator may turn the handle 125 (23) counter-clockwise as viewed in Figure 2 into the third dotted line position which causes the end of the rod (53) to rest on the last tooth (58) and may leave the handle in this position until a sufficient supply of 130 carbonated water is obtained. In this latter

position none of the passages in the valve (22) registers with any of the ports in the valve housing and no liquid is dispensed.

It will be noted in view of the foregoing that in the operation of my faucet the handle snaps into the various port alining positions through the action of the tooth disk (57) cooperating with the resilient pressure of the valve stem (53) wedging between the teeth; also, that although the operator may freely turn the faucet handle to pass over ports not wanted in order to arrive at the port desired, this is done quickly with so little escape of the undesired syrup that it is of no consequence in view of the great gain in simplicity and speed of operation as against the complexity of faucets wherein auxiliary valves are worked by another motion of the handle after arriving at the proper place.

I claim:

1. In a dispensing faucet for a soda fountain, a housing having a passage connecting a source of carbonated water and a plurality of passages connecting, respectively, sources of various syrup flavorings, a rotatable valve seated within said housing and adapted to shut off all of said passages, a plurality of syrup discharge ports in the valve so arranged as to successively register, each respectively, with one of the syrup flavoring passages upon rotation of the valve and additional discharge ports in the valve communicating each, respectively, with said syrup discharge ports adapted to register with the carbonated water passage upon the registering of the syrup passage and port.

2. In a dispensing faucet for a soda fountain, a housing having a passage connecting a source of carbonated water and a plurality of passages connecting respectively separate sources of flavoring syrups, a rotatable valve seated in said housing having discharge ports adapted to successively register with said passages in predetermined order upon rotation of the valve, a source of renewal

water for said source of carbonated water, means actuated by the rotation of the valve for opening said source of renewal water to said source of carbonated water between the points of such successive registering of the passages with the ports and of closing it during such registering.

3. In a dispensing faucet for a soda fountain, a housing having a passage connecting a source of carbonated water and a plurality of passages connecting respectively separate sources of flavoring syrups, a rotatable valve seated in said housing having discharge ports adapted to successively register with said passage in predetermined order, a handle for rotating the valve, a source of renewal water for said carbonated water, a service cock on said source having a spring actuated operating stem, a toothed member secured to the valve for rotation therewith arranged to bear against said stem to intermittently operate same through the action of the teeth upon rotating the valve and to indicate between points of operation the registering positions of the passages with the ports.

4. In combination, a dispensing faucet of the character described allowing liquids to be drawn from various sources in various combinations, a handle for turning the faucet and means associated with the faucet for automatically replenishing one of the sources while the faucet is turned comprising a supply pipe leading to the latter source having a valve therein, a valve stem associated therewith adapted to lift the valve off its seat and a tooth disk associated with the faucet engaging the end of the valve stem for intermittently actuating the same by the teeth when the faucet is turned.

5. In a dispensing faucet as specified in claim 1, a gasket positioned between the plurality of passages and the valve having openings therethrough registering with the passages.

WILLIAM N. DAMON.
